UNITED STATES PATENT OFFICE

CHARLES W. COKER, OF HARTSVILLE, SOUTH CAROLINA, ASSIGNOR TO SONOCO PRODUCTS COMPANY, OF HARTSVILLE, SOUTH CAROLINA, A CORPORATION OF SOUTH CAROLINA

SPINDLE FOR ENGAGING AND WINDING TEXTILE FABRIC

Application filed September 11, 1923. Serial No. 662,147.

This invention relates to a portable, elongated, cylindrical spindle adapted to yieldingly engage the straight end edge of an elongated strip of textile fabric or similar thin flexible material and by rotation to draw said fabric from a source of supply and wind it into a roll around it and to act as a support for the roll during transportation to the place of use and in unwinding. It is particularly adapted for use as the drawing roll for cord tire fabric. Heretofore in winding fabric and particularly, cord tire fabric, embodying as it does comparatively few and comparatively weak transverse strands, it has been found difficult to satisfactorily attach the end of the fabric to the roll for winding and to satisfactorily detach the end when the roll is unwound in use. The usual practice has been to place the end of the fabric on the roll and drive tacks through it into the roll at intervals longitudinally of the roll but this has many objectionable features. It requires great care, close attention and consumes considerable time in all cases to accomplish an engagement with the edge in correct alignment on the roll and with the fabric smooth and without wrinkles longitudinally of the roll and it requires experience to do it satisfactorily even then. Detaching the fixedly connected end from the roll when the fabric is unwound in use is also troublesome. The tendency of the spaced tacks to unevenly stretch the fabric at the end is also objectionable. My present invention is intended and adapted to avoid these defects in construction and resulting troubles in operation and to make it easy to attach the end edge of the fabric to the spindle in properly aligned position and without wrinkles transversely and to hold said edge firmly at all points throughout its length and to permit it to be automatically disengaged from the spindle when it is reached in unwinding the fabric for use. The invention furthermore has the advantages of great simplicity of construction, low cost of manufacture, lightness and a surface including the clamping part which will prevent displacement of the fabric by slipping. In the specific embodiment of the invention shown for purposes of illustration, it con-

sists of an inner pasteboard tube of uniform diameter and an outer tube-like member surrounding said tube throughout the greater part of its circumference, but having a part between parallel longitudinal lines removed, thus having a longitudinal slot with spaced parallel edges. This tube-like member is also made of pasteboard and is formed with its interior diameter approximately the same as the outer diameter of the tube on which it fits. The outer split tube closely fits the inner tube and its resiliency causes it to yieldingly and uniformly press the fabric under it against the inner tube and this pressure is increased if the inner diameter of the outer tube is made somewhat less than the outer diameter of the inner tube.

The invention and its novel features will be more fully understood from the following description and claims taken with the accompanying drawings.

In the drawings:

Fig. 1 is a perspective view of a well known metal winding bar projecting from the end of the tubular spindle constituting the present invention, the end of the spindle being shown in cross section and a partly wound roll of fabric thereon shown in cross section in a different plane from that of the spindle;

Fig. 2 is a cross section on the line 2—2 of Fig. 1;

Fig. 3 is a cross section of the tube and surrounding split tube constituting the present invention; and

Fig. 4 is a cross section like Fig. 2 showing the fabric extending entirely around the inner tube.

Referring first to Fig. 3, which shows an embodiment of the invention only and thus illustrates it most clearly, 10 represents the inner tube of the spindle and 11' the outer split tube and it will be noted that the parallel edges 12 and 13 of the split tube are spaced apart leaving an exposed surface of the inner tube between them on which the end edge of the fabric may be placed and adjusted to proper alignment before being inserted under the edge of the split tube for clamping engagement preparatory to winding. In inserting the end edge of the fabric under the

edge 13, for instance, it is necessary, of course, that it shall be moved radially outward from the surface of tube 10 and held in its outer position during the movement of the end edge of the fabric into properly adjusted position beneath it and although this may be easily done manually by one person while another adjusts the fabric or with a little experience it can be successfully done by one person alone, it is preferred to insert a small wedge circular in cross section at each end of the spindle between the edge portion of the split tube and the outer surface of the inner tube at a sufficient distance from the edge to permit the end edge of the fabric to extend under said edge the desired distance for clamping engagement. This last arrangement makes it possible for a single person to easily, quickly and accurately attach the end edge of the fabric to the spindle for winding. The straight edge of the split tube serves as a closely adjacent guide for the longitudinal alignment of the end edge of the fabric on the spindle and since one wedge will be removed before the other the operator may remove any wrinkles then formed by holding the fabric in extended position with one hand while he removes the other wedge with his other hand.

As will be seen by reference to Fig. 2, the fabric extends, from its end position 14 under the edge portion 13 of the split tube 11, in the same direction around the exposed surface of tube 10 over edge 12 and thus in starting the winding after the end edge is clamped any resistance of the fabric to the necessary longitudinal movement in winding will be in a direction which will tend to, in a sense, pull the end edge of the fabric in a direct line out of the clamp. The uniform radial pressure on both sides of the clamped end of the fabric and a slight roughness of the tubes in contact with it will however cause sufficient frictional resistance uniformly distributed throughout the width of the fabric to prevent any possible slipping or disarrangement of the clamped end. Each layer of the fabric after the first by its tension furthermore increases the clamping pressure. This arrangement furthermore has a very valuable function and advantage in unwinding the fabric for use since when the end is reached, the tension on the fabric will be in the right direction to most easily and with the least possible frictional resistance draw it from its position below the clamping edge 13 without any injury to even the clamped end of the fabric. It will be noted that in this operation the tension of the fabric tends to lift the edge 13 from the surface of the tube thus aiding in the release.

The outer split tube shown in Figs. 1 and 2 is of greater thickness than that shown in Fig. 3 and has a longitudinally extending depression 15 on its inner surface midway be-

tween its parallel edges formed by scoring which the form shown in Fig. 3 does not have. The reason for this is that if the semi-cylindrical tube is sufficiently thin it may be opened to the desired extent by a spring action in assembling and in use without danger of breaking or splitting but it is sometimes desired to use tubes of greater thickness for purposes of strength and rigidity and the scoring makes this possible without danger of breaking during the necessary opening.

It will of course be understood that the length of the tubular spindle varies with the width of the fabric to be wound on and carried by it.

The tubular spindle may be detachably supported and rotated by any suitable known means since the specific structure of such means forms no part of the present invention. In the form shown in Fig. 1 the support consists of a metal winding bar 16 having a cylindrical outer surface of such diameter as to enter and fit the inner surface of the inner tube of the spindle. It is provided with a longitudinal slot 17 between its ends and encloses a longitudinally extending metal strip 18 pivoted at its inner edge 20 with its outer, rather sharp, edge 19 normally resting against one longitudinal edge of the slot 17 and terminating at or very slightly beyond the cylindrical outer surface of said bar. This pivoted strip serves as automatic means for so engaging the inner surface of the inner tube 10 of the spindle as to cause it to rotate with the bar 16 when that bar is turned in one direction. When the spindle is in place on the bar 16 and the end 14 of the fabric is clamped to the spindle and the outer portion 19 of the metal strip 18 rests against the edge 21 of slot 17 with its rather sharp edge engaging, under slight pressure, the inner surface of tube 10 a rotary movement of the bar 16 in the direction indicated by the arrow in Fig. 2 to wind the fabric will tend to move the spindle with it and although the tension of the fabric resisting it will tend to cause slight rotary slipping of the spindle on the bar, the contact of the inner surface of tube 10 with the edge 19 will quickly turn strip 18 on its pivot sufficiently to make it so firmly engage the inner surface of tube 10 as to prevent any slipping. When the winding of a roll is finished the rotary connection between the bar and spindle may be released by a slight reverse relative rotary movement.

The metal winding bar 16 is solid except for the longitudinal groove 17 which is preferably V-shaped in section as shown in Fig. 2.

Although as above stated, the gripping action of the tubes on the fabric will ordinarily be sufficient to prevent the fabric from being withdrawn in starting the operation of winding or during winding where the end edge of

the fabric extends under the edge of the outer tube for only a short distance, it will be understood that the end edge of the fabric may extend under the edge of the outer tube and around the inner tube as far as may be desired. For instance it may extend entirely around the inner tube to the opposite edge of the outer tube, as shown in Fig. 4. In this instance the end edge of the fabric is, of course, first placed on the inner tube in longitudinal position and is wound around that tube one turn and then the edges of the outer split tube are separated and the two tubes are then brought together longitudinally. This arrangement increases the gripping action both because of the increased contact surface and because of the increased diameter of the inner tube due to its winding of yarn.

Under some circumstances and particularly where it is desired that the end edge of the fabric extend only a short distance under the edge of the outer tube it is advisable to secure one edge portion of the outer split tube to the outer surface of the inner tube by paste or other adhesive material, 22, as shown in Fig. 2, in order to avoid any possibility that the outer split tube will turn on the inner tube.

As heretofore stated, when the roll of fabric on the spindle has been transported to the place of use and is being unwound, it is not necessary to stop the unwinding movement to release the end of the fabric from the spindle since it will be automatically released by the tension of the fabric when it is reached and the pull is direct. A very useful and valuable feature of the present invention is that neither the fabric nor the spindle is injured in the least during the winding or unwinding and that the spindle may be used many times.

Although a specific embodiment of the invention has been shown for purposes of illustration, it will be understood that it is not limited to details beyond those specified in the claims.

Having thus described the invention what is claimed as new and desired to be secured by Letters Patent is:

1. A portable spindle for clamping and winding textile fabric comprising in combination, a cylindrical pasteboard tube, a split pasteboard tube closely and yieldingly fitting under tension and largely surrounding said tube substantially throughout its length, having spaced parallel longitudinal edges, the inner side of the split tube being scored longitudinally to facilitate lateral bending without breaking when opened, whereby the straight end edge of the fabric to be wound may be inserted under one straight edge and securely clamped by it to the inner tube of the spindle.

2. The combination with a winding bar

of a hollow cylindrical tube of fibrous material adapted to be placed concentrically on said bar and to turn therewith, said tube having an unbroken outer cylindrical surface, and an elongated longitudinally split cylindrical tube of fibrous material fitting over said hollow tube and gripping the same by spring action, one edge of said split tube being adapted to be raised to receive thereunder one end of a web of fabric to be wound on said tubes, and the opposite edge of said tube being permanently attached by adhesive to the said hollow cylindrical tube.

3. The combination with a winding bar of a hollow cylindrical tube adapted to be placed concentrically on said bar and to turn therewith, said tube having an unbroken outer cylindrical surface, and an elongated longitudinally split cylindrical tube fitting over said hollow tube and gripping the same by spring action, one edge of said split tube being adapted to be raised to receive thereunder one end of a web of fabric to be wound on said tubes, said split tube being scored longitudinally at a distance from its longitudinal edges to facilitate raising one of said edges from the hollow cylindrical tube.

In testimony whereof I hereunto affix my signature.

CHARLES W. COKER.
